UNITED STATES PATENT OFFICE.

ANDREW W. SODERBERG, OF MUNHALL, PENNSYLVANIA.

REGENERATIVE FURNACE.

Application filed June 10, 1921. Serial No. 476,517.

My invention relates to regenerative furnaces, and particularly to means for regulating the flow of the incoming and outgoing gases in such furnaces, and has for one of its objects the provision of improved regulating means adapted to be incorporated in furnaces of well known and approved construction.

Another object is to provide novel means for operating said regulating means when it is desired to reverse the furnace.

Still another object is to provide a furnace regulating means having the novel constructions, combinations, and arrangement of parts illustrated in the accompanying drawings, described in the following specification and particularly pointed out in the claims.

Referring to the drawings, Figure 1 is a top plan view of a regenerative furnace having my invention applied thereto.

Figure 2 is a rear view thereof.

Figure 3 is a sectional plan thereof.

Figure 4 is a side elevation thereof.

Figure 5 is a longitudinal sectional elevation thereof.

Figure 6 is a cross sectional elevation on the line VI—VI of Figure 5.

Figure 7 is a detail sectional elevation of one of the reversing valves.

Referring more particularly to the drawings, the furnace illustrated therein is of a well known and approved design consisting of side walls 2, end walls 3, top 4 and hearth 5. A wide air port 6 and a combined air and gas port 7 are arranged at each end of the furnace, the combined air and gas port 7 being below the wide air port 6 which extends across the whole width of the furnace.

The furnace is of duplicate construction at each end, therefore the detailed description of one end will suffice for both, and the same reference numerals will be applied to duplicate parts at both ends.

The air port 6 is connected to a slag pocket 9 by vertical flues 10 and 11 which communicate with the port adjacent the sides thereof, and the combined air and gas port 7 is connected to the slag pocket 9 by a vertical flue 12.

Horizontal passageways or flues 13 and 14 connect the slag pocket 9 with regenerators 15 and 16, respectively, which are connected by horizontal passageways or flues 17 and 18, respectively, through valves 19

and 20 to the stack flue 21 or branch air flue 22 according to the position of the valves. The branch air flue 22 is connected to a main air flue 23 leading from a blower or fan 24, and the stack flues lead to and communicate with a stack 25.

The valves 19 and 20 are of duplicate construction and comprise a housing 26 having its bottom end in communication with the stack flue 21, and an extension or lean-to portion 27 in communication with the flue leading to the regenerator.

The valve housing 26 is provided intermediate its ends with a valve seat 28 and at its lower end at the point of communication with the stack flue 21 with a second valve seat 29. A vertically movable valve 30 is mounted on a stem 31 in the housing 26 and is adapted to be moved vertically by screwing the hand wheel 32 so as to seat on either of the valve seats 28 or 29.

The branch air flue 22 communicates with the valve housing 26 at a point above the valve seat 28, therefore if the valve 30 be moved vertically and seated against the seat 28 the air cannot flow through the valve to the flues entering the regenerators, but the valve will be open for communication to the stack, which is the position of the valves on the discharge end of the furnace. However, the valves on the firing end of the furnace will be seated against seats 29 so that communication with the stack will be shut off and communication will be opened from the air flues to the regenerators.

Gas is admitted to the combined air and gas port 7 through suitable burner ports 34, which extend from the side of the furnace into the port 7 and have gas pipes or mains 35 entering an appreciable distance therein. The mains 35 are provided with suitable valves 36 for controlling the supply or volume of gas, and are connected with a supply main 37.

The air flues 10 and 11 leading from the slag pocket 9 are provided with dampers or valves 39 and 39^a, respectively, of the butterfly type, which are preferably of the water cooled cast type, and comprise a hollow body portion 40 and an integral hollow trunnion 41. An integral dividing or circulation wall 42 extends centrally through the trunnion 41 and joins a dividing baffle 43 in the body of the valve which terminates short of the ends thereof to allow

circulation therearound. The trunnion 41 is provided with inlet and outlet ports connected with water pipes 44 and 45 to provide circulation of cooling water through the one side of the trunnion into the valve body around the baffle 43 and out through the other side of the trunnion 41.

The valve has its trunnion 41 journaled in a suitable water cooled bearing 46 mounted in the furnace side wall.

A water cooled valve seat 47 is mounted in and is flush with the walls of the air flues 10 and 11 and the valve bodies 40 are adapted to aline therewith when they are in closed position.

The valve seat 47 is formed integral with the bearing 46 and is provided with water circulation pipes 48 and 49 which are cast therein and consequently form an integral part thereof.

As shown, the valves 40 are located only in the air flues 10 and 11, but when found desirable or necessary an additional valve 40 will be provided in the central flue 12. The location of the valves 40 may be changed from that shown to any suitable point in the length of the flues between the regenerators and the furnace hearth.

The side walls 2 of the furnace are provided with arches 50 at a point above the valve seat 47, which arches extend the entire width of the flues 10 and 11 and provide for removal of the portion of the side wall immediately surrounding the valve seat and valve to allow for repairs or replacement, without materially interfering with the operation of the furnace.

The valves 39 and 39^a at each end of the furnace are connected together by a system of levers and operated simultaneously by a pair of single acting hydraulic cylinders 52 and 53. A crank arm 54 is secured on the trunnion 41 of the valve 39 and connected by a link 55 to a crank arm 56 on a connecting shaft 57 extending across the end of the furnace journaled in suitable bearings 58.

A crank arm 59 is secured to the other end of the shaft 57 and is connected by a link 60 to one end of a lever arm 61 secured intermediate its ends to the trunnion 41 of valve 39^a and having its other end secured to the piston rod 62 of the pair of cylinders 52, 53.

The cylinders 52 and 53 at each end of the furnace have their inlet ports connected together by pipes 63, 64, so that fluid will enter both cylinders 52 and both cylinders 53 simultaneously, thus operating the valves at each end of the furnace at the same time.

It will be understood that when the valves are assembled the valves at one end are assembled in the reverse position to the valves at the other end, that is, the valves at one end are assembled in their open position, while the valves at the other end are assem-

bled in their closed position, so that when the cylinders 52 are operated together one pair of valves will be opened while the other pair will be closed and the operation will be reversed when the cylinders 53 are operated. The pipes 63 and 64 are connected to fluid pressure pipes 65 and 66 leading from a four-way valve 67 of any well known construction, which has inlet and outlet pipes 68 and 69 communicating therewith.

It will be understood that single acting cylinders of the design used in operating the valves 39 and 39^a only have a single port which is connected with the pressure pipe. However, as the fluid pressure is forced into one cylinder the piston moves into the other cylinder and forces the fluid out through the port of that cylinder through which it entered. The control of the fluid pressure and exhaust fluid is governed entirely by the four-way valve 67.

While I have shown fluid cylinders for operating the valves 39 and 39^a, other mechanism may readily be employed, such as a system of hand levers, or electric motors.

Those skilled in the art will readily see that I have provided a system of damper controls for the air flues of open hearth furnaces that may readily be applied to existing furnace constructions without materially altering their design.

The operation of the furnace is as follows: Assuming that the valves 39 and 39^a are in the position shown in the accompanying drawings, the furnace will be fired at the end in which the valves are closed, since less port and flue area is needed to admit sufficient air to support combustion, than is necessary to allow the escape of the products of combustion.

Air will be forced through the regenerators 15 and 16 communicating with the air ports of the end of the furnace being fired, and gas will be admitted through the burner ports 34, thus forming a combustible mixture, the proportions of which may be varied by regulating the valves 39, 39^a, and the products of combustion will pass out through the ports at the opposite end of the furnace.

When it is desired to reverse the furnace, the valves 19 and 20, controlling both sets of regenerators 15 and 16, are reversed and the gas is shut off from the burner ports in the firing end of the furnace and turned on in the burner ports at the other end. The fluid pressure is then turned into the cylinders 52 at each end of the furnace and the position of the valves 39, 39^a reversed in accordance with the reversal of the firing of the furnace.

Various modifications and changes in design and combination of parts will readily

suggest themselves to those skilled in the art and may be made without departing from the spirit of my invention as defined in the appended claims.

5. I claim:—

1. In a regenerative open hearth furnace having a hearth, a combined gas and air port, and an air port at each end of said hearth, a single slag pocket arranged below said ports at each end of said furnace, and vertical flues connecting said air ports and said combined gas and air ports with said slag pockets, butterfly type valves mounted in said flues connecting said air ports, and hydraulic cylinders having suitable lever connections with said valves, and adapted to simultaneously operate the valves at both ends of said furnace.

2. The combination with a regenerative furnace having a plurality of air flues at each end thereof, of means for controlling the flow of air through some of said flues, said means comprising water cooled butterfly valves having integral trunnions journaled in water cooled bearings mounted in the side walls of said furnace, and means for simultaneously operating the valves at both ends of said furnace.

3. The combination with a regenerative furnace having a plurality of air flues at each end thereof, of water cooled butterfly valves mounted in said flues for controlling the flow of air through said flues, operating levers connecting the valves at each end of

the furnace, and means for simultaneously 35 operating the operating levers at both ends of said furnaces.

4. The combination with a regenerative furnace having a plurality of air flues at each end thereof, of hollow water cooled butterfly valves mounted in said flues for controlling the flow of air through said flues, said valves being provided with integral trunnion members journaled in suitable 45 bearings mounted in the side walls of said furnace, means for operating said valves, and water cooled valve seats rigidly mounted in the side walls of said flues.

5. The combination with a regenerative furnace having a plurality of air flues at 50 each end thereof, of hollow water cooled butterfly valves mounted in said flues for controlling the flow of air through said flues, said valves being provided with integral trunnion members journaled in suitable 55 bearings mounted in the side walls of said furnace, water cooled valve seats rigidly mounted in and flush with the side walls of said flues, operating levers connecting the valves at each end of the furnace, and fluid 60 operated cylinders for simultaneously moving said operating levers at each end of said furnace to reverse the position of said valves.

In testimony whereof I have hereunto set 65 my hand.

ANDREW W. SODERBERG.
